DESIGN FOR A GAME BOARD

Aubrey Riddle, Owensboro, Ky.

Application January 20, 1940, Serial No. 89,611

Term of patent 14 years

To all whom it may concern:

Be it known that I, Aubrey Riddle, a citizen of the United States, residing at Owensboro, in the county of Daviess and State of Kentucky, have invented a new, original, and ornamental Design for a Game Board, of which the following is a specification, reference being had to the accompanying drawing, forming part thereof.

I claim:

The ornamental design for a game board, as shown.

AUBREY RIDDLE.
